(57) **CLAIM**

The ornamental design for a vehicle head light, as shown and described.

DESCRIPTION

FIG. 1 is a front and left side perspective view of a vehicle head light.

FIG. 2 is a front view of the vehicle head light of FIG. 1.
FIG. 3 is a left side view of the vehicle head light of FIG. 1; and,

FIG. 4 is a top view of the vehicle head light of FIG. 1.
The dashed lines showing the various parts of the vehicle are for illustrative purposes only and form no part of the claimed design.
